[57] CLAIM

The ornamental design for a driver interface module or
similar article for a vehicle monitoring system, as
shown.

DESCRIPTION

FIG. 1 is a top, front, left end perspective view of a
driver interface module or similar article for a vehicle
monitoring system showing our new design;
FIG. 2 is a right end elevation view thereof;
FIG. 3 is a bottom plan view thereof;
FIG. 4 is a rear elevational view thereof; and
FIG. 5 is a front elevation view thereof.
